UNITED STATES PATENT OFFICE

FREDERICK P. GARDNER, OF NEW YORK, N. Y., ASSIGNEE TO FABRICORD INCORPORATED, OF NEW YORK, N. Y., A CORPORATION OF NEW YORK

FIBER-CLEANING MACHINE

Application filed February 4, 1928. Serial No. 251,829.

This invention relates to machines for separating and cleaning fiber from fiber bearing plants such as hemp, flax, jute, ramie or the like, and has for its object the provision of means for obtaining long ribbon-like fiber or fine hair-like fiber from fiber yielding plants, in the form of line fiber or tow as may be desired.

Another object of the invention provides 10 means for removing the woody core even from green or unretted fiber stalks, said means co-operating in conjunction with means for cleaning said fiber as a continuous operation.

A still further object of my invention includes the provision of a simple and comparatively inexpensive machine which may be readily moved about in the field and operated where the fiber producing plants are grown and harvested. The machine is, moreover, 20 capable of efficiently cleaning green or wet fiber yielding straws, or it may be used for efficiently cleaning the retted and dried fiber yielding straws or straws in any degree of retted condition as occasion may require.

25 A further object includes the construction and arrangement of adjustably held breaking blades to co-act with variably spaced moying striker blades to break and free the woody core from the fiber.

30 A still further object includes the provision of means for receiving and conveying away from the breaker device the fiber whether "line or tow", "green or retted" without snarling, tangling or winding and delivering said fiber in an orderly and uniform manner. By reason of its construction and operation I also 35 polish the fiber by said conveying means.

I obtain these objects by the construction shown in the accompanying drawings in 40 which—

Figure 1 is a side elevation shown partly in section of a preferred form of construction;

Fig. 2 is a view taken from the front or 45 left hand side of the machine of Fig. 1;

Fig. 3 is a view taken from the right hand side of the machine of Fig. 1;

Figs. 4 and 5 are front and plan views respectively of the stationary breaker blades; 50 and

Figs. 6 and 7 show respective sections of the vertically and of the horizontally disposed members operating as conveyors and scrubbers.

The same reference numerals refer to like parts throughout the several views.

The known machines for obtaining and cleaning fiber from such plants as hemp, flax, jute, and the like, required for successful operation that the plant stalks be retted and 60 dry so as to break the woody core and then separate the broken woody core or chives from the fiber. In the operation of the known machines some long fiber and much short crumpled fiber was always produced. 65

By the use of my improved fiber cleaning machine I am enabled to successfully, thoroughly and quickly clean the fibers from fiber bearing plant stalks that are taken directly from the field, unretted and even undried. 70 My machine is, moreover, capable of producing any grade from long ribbon-like fiber to fine tow from either green or wet straw, or from the retted and dry stalks.

In the accompanying drawings I have 75 shown a preferred form of construction which is suited for the objects stated. I do not, however, desire to be understood thereby as having thus limited myself, as various modifications falling within the spirit and scope of 80 my invention will suggest themselves to those versed in the art.

Referring now to the drawings, I provide a frame 10 having a base 11 for supporting the elements that constitute my improved 85 fiber cleaning machine.

On the upper part of the frame, in suitable bearings, I provide feed rolls 12, 13 and 14, 15 having gears 16 on the ends for driving said rolls in pairs, to thereby feed the fiber 90 bearing stalks or straws into the machine at a uniform speed and in an orderly manner.

Adjacent the feed rolls just described I provide a number of horizontally disposed blades 17, 18, 19, 20. These blades which I 95 will call "breaker blades" are provided with slots 21 through which extend bolts 22 for securing together said blades with spacer blocks 23. The blades are adjusted as a unit by means of set-screws 24 operating in the guide 100

plate 25. These blades are beveled as shown and are adjustable vertically by varying the thickness of blocks 23. They are also adjustable in horizontal positions independently of each other by reason of slots 21 and bolts 22. 5 This construction permits adjustments of the breaker blades 17, 18, 19 and 20 for the purpose stated more fully hereinafter. A small roll 26 supplements the pairs of feed rolls 10 in guiding the material over the upper breaker blade into breaking position.

A cylindrical member 27 having radically disposed blades 29 is mounted on a shaft 28 in the upper part of the machine frame. This 15 shaft is provided with a drive pulley 33, a flywheel 34 and sprocket 35. A chain 36 drives the machine from the drive shaft sprocket 35, as will be stated more fully below.

It will be noted that the blades 29 (hereinafter to be known as the "striker blades") 20 are set in slots 30 and are, in a preferred construction, grouped in pairs with a narrow space 31 nearly filled to the beveled striking edge 32 of the blades, which space is alternated 25 by a wider space 31'. This wider space is more open to provide room for the longer pieces of the woody core of the plant stalk and to effectively remove larger pieces of the woody material in the operation of the machine. The slots 30 are variously spaced and 30 combinations of two, three or even more blades may be made for different grades of material to be produced from widely differing fiber producing plants.

35 From the construction shown in Fig. 1 it will be noted that the breaker blades are beveled from the under side, while the striker blades are beveled from the upper side and that the successive breaker blades from the 40 top down are adjusted to provide varying distances between the edges of the striker blades and the breaker blades. As an example it is found that a distance of $\frac{3}{16}$ of an inch at the upper blade will produce good line fiber 45 while a distance of $\frac{1}{16}$ will yield mostly tow. The breaker blades are, therefore, adjusted to meet the conditions of the material and to supply the desired product. In the drawing I have shown the successive lower blades (i. e. 50 18, 19 and 20) to be each set back a little farther but in some cases this regularity will vary, that is the second blade may be set back a little more than the third, to thus provide for more pronounced breaking action. Conditions requiring more pronounced 55 breaker action are apt to arise where the straw is green or wet, or both green and wet.

I will now describe the conveying and scrubbing mechanism, whereby the fiber is 60 carried away from the breakers and is freed of any adhering pieces of woody core or chives.

Immediately beneath the striker and breaker blades I provide means for receiving 65 and carrying away the line fiber, tow or in-

termediate fiber. Said means comprises a system of aprons or conveyors arranged in vertical or receiving section and in horizontal or polishing section. The aprons or conveyors are of open construction of wooden or metal slats (45 or 46) held on chains 42' whereby the fiber is separated from any adhering woody core pieces which by reason of the open conveyor fall through the conveyors and sprockets. 70 75

The chains 42' pass over sprockets 40 suitably spaced and supported. The vertical portion of apron 41 and its adjacent apron 42 move in unison and sprocket 43 is so placed that apron 42 keeps the fiber from traveling with the striker blade and tangle or wind the fiber, this is a great advantage as it prevents winding and tangling. Apron 41 with its adjacent apron 42 grabs and pulls the broken and partially cleaned fiber material as it leaves the striker blades by reason of the nearness of the apron 42 when it passes over its upper supporting roll 43. A lower drive roll 44 supports the apron in position to engage and guide the fiber material with the aid of 80 apron 41. Both aprons are alike in construction and they travel at the same speed so as to hold the fiber between slats 45 and 46 which are staggered to more firmly hold the fiber. The portion of the conveyor just described 85 carries the fiber vertically and will be known as the "vertical" portion of the conveyor system. 90 95

It will be noted that conveyor 41 passes over a second sprocket 47, which is directly 100 below sprocket 40, and then said conveyor passes horizontally over a third sprocket 48 to thus form the "horizontal section". A short horizontal apron 49, supported and driven from sprockets 50 and 51 forms with 105 the horizontal section the "polishing" section of the conveyor, because slats 52 on conveyor 49 are in contact with slats 45 on conveyor 41 and conveyor 49 moves faster than conveyor 41. The distance between slats 45 and 52 (Fig. 7) can be adjusted to give any degree of polishing to the fiber and to remove 110 adhering pieces of woody core.

The conveyor sprockets are driven by a chain 53 from a sprocket 54 which is geared 115 with drive 55 on sprocket 56. It will be noted that chain 53 passes over idlers 61 and 62 in order to give the right direction to sprocket 51. Sprocket 50 is driven from sprocket 44 by a chain or belt 57. The feed rolls 13 and 120 15 are driven from chain 58 and roll 26 is driven by chain 59. I have shown and described sprockets and chains as the driving means, but obviously other means as pulleys and belts or their equivalents, may be employed if desired.

The machine may also be mounted on 125 wheels or sledges (not shown) for readily moving the same from place to place in the field where the fiber plants are grown and 130

harvested, thus saving the cost of hauling the uncleaned straw or plant stalks long distances to the machine as has heretofore been the practice.

Having now described my invention, what I claim is:

1. In a fiber cleaning machine, a plurality of fixed blades over which fiber yielding plants are adapted to be bent and broken, in combination with a plurality of striker blades, means for moving said striker blades in fixed paths to successively pass in front of said fixed blades for breaking the woody core out of said fiber, a conveyor for receiving and carrying the fiber, and means co-acting with said fiber receiving and carrying conveyor for scouring said fiber as it is carried on said conveyor.

2. In a fiber cleaning machine, the combination of breaker blades having beveled edges and means for securing said blades in adjusted positions, of a cylindrical member having slots offset by ridges, blades held in said slots adjacent said ridges, said blades being spaced to accommodate chives of varying lengths, an apron for receiving and conveying fiber material and a polishing apron coacting with said first named apron to remove adhering wood parts.

3. In a fiber cleaning machine, a plurality of blades arranged vertically one above the other, said blades having beveled edges over which fiber plants are bent and broken, striker blades and means to rotate said striker blades in front of the beveled edges of said vertically arranged blades, conveyor sprockets to support said conveyor in planes substantially at right angles to each other and independent conveyor members cooperating with said conveyor sections.

4. In a fiber cleaning machine, fiber breaking mechanism in combination with uniformly moving apron section followed by an apron section of members disposed face to face and moving at different rates, said sections disposed at an angle to each other.

5. In a fiber cleaning machine, fiber breaking mechanism in combination with uniformly moving apron section vertically disposed and formed by two aprons moving at substantially the same rate and a second apron section comprising members one of which moves at a rate differing from that of its companion, said second apron section disposed at an angle to said first named section.

6. In a fiber cleaning machine, fiber breaking mechanism in combination with uniformly moving apron section vertically disposed and formed by two aprons moving uniformly face to face and having slats arranged in staggered relation, a second apron section disposed to move at an angle to said first named section, and means for moving a portion of said apron section faster than its opposing portion.

7. In a fiber cleaning machine, the combination of a plurality of breaker blades and means for supporting said blades at predetermined positions, means for feeding fiber bearing plant stalks over said blades, of a cylindrical member mounted to rotate in front of said blades, said cylindrical member having spines and parallel grooves in the surface of said cylindrical member, striker blades set in such grooves for bending and breaking said plant stalks when said cylindrical member is rotated, and a conveyor system cooperating with said striker blades to receive and remove the fiber from said striker blades to prevent the fiber from winding about the cylindrical member.

In testimony whereof I have hereunto set my hand this 1st day of February, A. D. 1928.

FREDERICK P. GARDNER.
